BLANK AND BOX MADE THEREFROM

Cutler D. Knowlton, Beverly, Mass., assignor to
 Hoague-Sprague Corporation, Lynn, Mass., a
 corporation of Massachusetts

Application September 8, 1930, Serial No. 480,517

9 Claims. (Cl. 229—32)

This invention relates to box-blanks and boxes made therefrom, it being particularly concerned with the production of wall-boxes of pasteboard or similar shell-material which are brought to 5 final form during their manufacture. The blanks may be made by the apparatus and method disclosed in the application in my name for Letters Patent of the United States, filed of even date herewith and bearing the Serial No. 480,518, 10 while such blanks may be transformed into a cover or box-part by the apparatus and method set forth in the application in my name filed in the United States Patent Office on July 7, 1930 and bearing the Serial No. 465,941.

15 The invention has as an object the provision of a blank from which may be formed a box-part both strong and attractive in appearance. This object I attain by a blank of shell-material having a body-portion and projecting wings with 20 extensions, in the margins of which wings are spaces shown as in the outer portions of corner-laps which furnish the extensions from certain of the wings, and stays secured to the wing-margins and extending in loops over the spaces. In 25 setting up the blank, the marginal spaces will receive both the reinforcing stays and extensions from the wings between the corner-laps. This prevents the protrusion of the edges of the walls bearing these extensions outside the plane of 30 the edges of the other walls, and the forcing of the stay-material into the spaces increases its resistance to tearing by softening it. The efficiency of the stays may be increased by disposing them in the marginal spaces in plural thicknesses, as by plaiting or doubling them. The 35 doubled stay may be caused to lie at those portions of the blank which, in the set-up part, are most liable to rupture.

40 A further object of the invention is to furnish a box-part possessing the characteristics of strength and symmetry above indicated. To this end, the set-up part has walls projecting from its body-portion of shell-material, the walls being provided with extensions which may be 45 in the form of corner-laps, in the outer margins of which are spaces. The corner-laps are secured to the intermediate walls, these last-mentioned walls being also provided with extensions secured to the corner-laps. To margins of the 50 walls, preferably those carrying the corner-laps, is attached stay-material extending over the spaces. The spaces in the corner-laps are occupied by both the stay-material and the wing-extensions, giving flush edges about the entire 55 periphery of the box-part. The plaiting or dou-

bling of the stay over the junctures of the side-wings and corner-laps, in the blank, results, in the set-up box-part, in an increased resistance to breaking at the meeting lines between the walls, or at the corners. In the finished box-part, the rough shell-material and stays are hidden by cover-material. The body and walls are separated from each other by creases, and adjacent to these creases said body and walls are displaced inwardly to form depressions and the 10 laminae of the shell-material separated while the box-part is in set-up form. Thus the corners are squared, the length of the walls is shortened, and stresses generated in the creases during the folding of the blank are released, so said walls 15 will remain more nearly at right-angles to the body.

The accompanying drawing shows a single embodiment of my invention,

Fig. 1 being a broken perspective view of the 20 improved blank;

Fig. 2, an enlarged broken perspective of a corner of said blank;

Fig. 3, a transverse section on the line III—III 25 of Fig. 2;

Fig. 4, a broken perspective view of the cover of my invention;

Fig. 5, a like view, enlarged, of the corner of the cover; and

Fig. 6, an enlarged section on the line VI—VI 30 of Fig. 4.

Referring to Figs. 1, 2 and 3, a blank B is illustrated which is especially adapted for the formation of the cover-part of a box, though its features are also applicable to box-bodies, the difference being chiefly one of proportion. This blank is shown as consisting of a principal integral layer of shell-material 10, which may be of pasteboard of substantial thickness, to which is glued 35 an inner lining-layer 12 and an outer cover-layer 14, of such relatively thin material as paper, concealing both faces of the rough shell. Broadly, both of these finishing layers may be considered as cover-material. Further, there is over each longitudinal edge of the shell, beneath the cover-paper, a folded strengthening strip or stay 16, which may be of tough paper of the grade known as kraft. This may be glued to the opposite margins of the shell, being looped over the edges. The blank has a central body-portion 18, usually 40 rectangular and elongated, from the longitudinal edges of which extend side-wings 20, 20, while from the intermediate edges project end-wings 22, 22, creases 24 dividing the side-wings and creases 26 the end-wings from the body. the opposite extremities of the side-wings project lateral extensions or corner-laps 28, the meeting lines of which are defined by continuations of the creases 26, which continuations, however, are shown as somewhat offset inwardly at 27, so, when the cover is set up, the corner-laps will lie smoothly within the end-wings, the latter furnishing the outer layers. The end-wings carry at their ends opposite the body-portion extensions 30, there being intermediate creases 32. All the creases 24, 26, 27 and 32 are preferably of the bead-type, in which the blank-material is pinched into a groove or depression of general U-form, the curved bottom of this groove coming upon the inside of the set-up cover. These creases facilitate the folding of the blank to cover-form without breaking of the constituent layers. In the pinching of the laminated material to the form of a bead-crease, the forces applied separate or slip the laminae over one another at the sides of the groove, but leave them connected at the bottom or curved portion and also where the sides of the crease join the connected portions of the blank. When the blank-wings are turned in at right-angles to the body-portion to furnish the cover-walls, the connected laminae of the creases resist the movement, and stresses may be set up tending to restore the walls to their initial positions and causing them to bulge outwardly. This tendency I correct as will later appear. Separating the corner-laps from the end-wings and their extensions are narrow slots 34, the ends 36 of which are rounded adjacent to the creases 26, 27. The outer edges of the corner-laps and immediately adjacent portions of the side-wings are cut away at 38, furnishing spaces or depressions to receive the end-wing-extensions in the setting-up of the cover, when these extensions are turned about the creases 32 to be secured against the inner faces of the corresponding end-wings and corner-laps. There results a symmetrical lower edge of the set-up cover lying in a single plane. The cover-material 14 is slit at 40 along the slot 34 adjacent to the inner edge of each corner-lap, and the portion projecting beyond the edge of the adjacent end-wing and its extension is tucked through the slot and then folded over and glued to said end-wing and extension at 42. This is to conceal the raw edge of the shell-material 10 at the corner of the cover after the blank has been set up. The loops of the stays 16, before the application of the cover-paper which conceals them, are depressed into the cut-out marginal portions 38 of the shell, preferably to form a central groove 44 with plait of the stay-material at each side. These depressions double the number of layers of the outer portion of each stay, giving four thicknesses instead of two, and thus increase proportionately the strength of that portion of each set-up cover which is especially subjected to strains. The softening of stay-material of the character of kraft-paper by its depression or crushing into the spaces 38 in the shell is also advantageous, in that a break in it is less liable to start in somewhat flaccid material at a localized point of weakness than in a stiff sheet. In addition to these advantages, the stay-material is better disposed in the cutaway portions of the shell, to allow the reception of the end-wing-extensions and to give the desired flush edge about the entire cover. The stays 16 at the outer face of the blank may lie over substantially the entire side-wings and corner-laps and be turned over the edge of the shell to meet the lining-material 12, being here narrower than at the opposite face. Folded-over

margins 46 of the cover-material along the side-wings and corner-laps overlie and conceal the edges of the shell-material, the inner faces of the stays and the edges of the lining-material.

In setting up or bringing the blank B to cover-form, as illustrated at C in Figs. 4, 5 and 6, the corner-laps 28 are first folded downwardly about the creases 27 substantially at right-angles to the side-wings 20, whereupon the latter are folded at the creases 24. During the movement of the side-wings to their final positions, at right-angles to the body-portion 18, the end-wings are turned down about the creases 26 against the corner-laps. The walls and corner-laps having been positioned, the end-wing-extensions 30 are folded first in and then up about the creases 32 until they contact with the inner faces of the corner-laps and end-wings. Glue having previously been applied to the chosen surfaces, as the inner sides of the end-wing-extensions, and to the portions of the end-wings with which the corner-laps are to contact, pressure is exerted to both cause the adhesion of the coated surfaces and to perfect the form of the cover. In this operation, the elements and relations described in the previously-mentioned application may be employed. The cover, with its open side down, has within it a form about which it has been folded, and the top of this cover is grasped between said form and an upper abutment-plate, the area of the latter being somewhat less than that of the upper face of the cover. The side-walls of the cover are resting upon ledges so its downward movement is prevented. These ledges may be upon walls which are movable inwardly toward the form. Between the end-walls of the cover and the form are spaces in which, at this point in the operation, are pressure-receiving hooks, opposite which, contacting with the outer faces of the end-walls, are movable pressure-applying abutments. With the ledges and the end pressure members holding the cover-walls against downward movement, the form and upper plate descend together with the cover-top clamped between them. The creases, however, are outside the engaged area both between the plate, the hooks and the pressure-applying abutments, or between the plate, the form and the side-walls. They are, therefore, free for a limited displacement under the influence of the descent of the plate and form. The elements engaging the walls may be so designed as to displace these walls somewhat inwardly. The effect of this is to upset the creases, those portions which were at the bottom or inside of each crease-groove being forced out at 50, while the outside of the groove, now at the interior of the cover, is displaced inwardly at 52. This effectively separates the laminae, thereby releasing the strains due to their connection and set up in folding. This relieves the walls from distorting forces which cause them to bow outwardly. At the same time, the pressure creates depressions at 54 over the top of the cover and at 56 along each wall between the corners. This has the effect of squaring the corners and of shortening the distance between said corners, further counteracting the tendency of the walls to bulge. It will be seen that, unlike the usual overbending procedure, the corrective forces are uniformly applied along the box-walls, so there will be no tendency to overstrain and rupture said walls.

In the set-up cover, the notches 38 in the shell-material are at the lower or outer edges of the corner-laps, and, since the stay-material 16 has

been depressed into these spaces, they are adapted to receive the turned-over end-wing-extensions 30, which complete the end-formations of the cover. Consequently, the edges of the walls 5 about the entire cover lie in a single plane, giving symmetry to the article. The rough shell-material and the reinforcing stays are entirely hidden by the lining-material 12 and the cover-material 14, the latter being folded over the 10 edges of the end-wings at 42 and the side-wings at 46, concealing the shell at these points. At the outer portions 58 of the corners, which, in such containers as shoe-cartons, receive the most 15 severe strains in use, the structure not only receives reinforcement of the looped stays, as do the intermediate portions of the side-walls, but, further, after these stays are doubled in thickness by the plaits at opposite sides of the groove 44, the corners are correspondingly strengthened. This furnishes a cover which offers effective 20 resistance to breakage at all vital points. In addition to their strengthening function, the double stays secured to the entire length of the side-walls stiffen these and increase their resistance to bulging.

Having described my invention, what I claim as new and desire to secure by Letters Patent of the United States is:

1. A blank for a box-part having a body-portion 30 of shell-material, wings projecting from the body-portion, corner-laps projecting from the extremities of opposite wings, extensions from the intermediate wings, there being depressions in the outer edges of the corner-laps and adjacent 35 portions of the wings, and stay-material attached to the wing- and corner-lap-margins and extending in loops over the depressions in said wings and corner-laps and lying in plaits in said depressions.

2. A box-part having a body-portion of shell-material, side-walls and end-walls projecting from the body-portion, the side-walls having extensions furnishing corner-laps adhesively secured to the end-walls, there being in the outer 45 margins of the corner-laps and adjacent margins of the side-wall depressions, extensions from the end-walls occupying the depressions and adhesively secured to the inside of the corner-laps, and stay-material adhesively attached to the 50 opposite margins of the side-walls and their corner-laps and extending in loops over their edges, the loops within the depressions in the side-walls and corner-laps being disposed in plaits.

3. A blank for a box-part having a body-portion 55 of shell-material, wings projecting therefrom, opposite wings having lateral extensions and the intermediate opposite wings having end-extensions, the extensions being separated from the wings by creases, there being depressions in the outer edges of the lateral extensions and in 60 the adjacent portions of the wings, and stay-material adhesively attached in a loop to the inner and outer margins of each wing carrying the lateral extensions, this stay-material lying 65 within both the extension- and wing-portions of the depressions.

4. A blank for a box-part having a body-portion 70 of shell-material, wings projecting therefrom, opposite wings having lateral extensions and the intermediate opposite wings having end-extensions, the extensions being separated from the wings by creases, there being depressions in

the outer edges of the lateral extensions and in the adjacent portions of the wings, and stay-material adhesively attached in a loop to the inner and outer margins of each wing carrying the lateral extensions, this stay-material being crushed 5 into the depressions and thereby rendered more flaccid and resistive to rupture at the creases between the wings and their lateral extensions.

5. A blank for a box-part having a body-portion 10 of shell-material, wings projecting therefrom, opposite wings having lateral extensions and the intermediate opposite wings having end-extensions, the extensions being separated from the wings by creases, there being depressions in the outer edges of the lateral extensions and in 15 the adjacent portions of the wings, and stay-material adhesively attached in a loop to the inner and outer margins of each wing carrying the lateral extensions, this stay-material being forced into the depressions to lie in layers exceeding in number those of a loop.

6. A box-part having a body-portion of shell-material, side- and end-walls projecting from the body-portion, corner-laps furnished by lateral extensions of the side-walls and adhesively secured to the inside of the end-walls, the corner-laps and adjacent portions of the side-walls having 25 spaces along their outer margins, and stay-material adhesively attached in a loop to the opposite sides of each side-wing and its corner-laps 30 and lying in the spaces, each end-wall being provided with an extension occupying the space outside the stays and secured to the inside of the corner-laps, the turned-over edges of the end-wall-extensions and the edges of the side-walls 35 lying in substantially the same plane.

7. A box-part having a body-portion of shell-material, side- and end-walls projecting from the body-portion, corner-laps furnished by lateral extensions of the side-walls and adhesively 40 secured to the inside of the end-walls, the corner-laps and adjacent portions of the side-walls having spaces along their outer margins, and stay-material adhesively attached in a loop to the opposite sides of each side-wing and its corner-laps 45 and being crushed into the spaces to give at the box-corners a softened reinforcement resistive to rupture, each end-wall being provided with an extension occupying the space outside the stays and secured to the inside of the corner-laps, the 50 turned-over edges of the end-wall-extensions and the edges of the side-walls lying in substantially the same plane.

8. In a pasteboard box produced by bending an integral blank including a laminated paper shell member of substantial thickness, a corner-construction wherein adjacent walls have been displaced inwardly after the box is in set-up form, thereby producing wall-depressions and eliminating stresses within the material of the corner-construction, which stresses would tend to cause the walls to bulge outwardly.

9. In a pasteboard box produced by bending a creased integral blank of laminated shell-material of substantial thickness, a corner-construction wherein adjacent walls have been displaced inwardly after they have been set up in box-form, thereby separating the laminae of the creases and eliminating stresses within the material of the corner-construction, which stresses would tend to cause the walls to bulge outwardly.

CUTLER D. KNOWLTON.
